(57) **CLAIM**

We claim the ornamental design for an air impact tool, as shown and described.

DESCRIPTION

FIG. 1 is a perspective view of an air impact tool.

FIG. 2 is a left side view of the tool of FIG. 1.

FIG. 3 is a right side view of the tool of FIG. 1.

FIG. 4 is a top view of the tool of FIG. 1.

FIG. 5 is a bottom view of the tool of FIG. 1.

FIG. 6 is a front end view of the tool of FIG. 1; and,

FIG. 7 is a rear end view of the tool of FIG. 1.

The broken line showing of the environment is for illustrative purposes only and forms no part of the claimed design.
